DERRICK REENFORCEMENT

Filed Jan. 13, 1928

BY
George A. Prevost.
ATTORNEY.

Patented May 14, 1929.

1,713,217

UNITED STATES PATENT OFFICE.

ARTHUR L. DAY, OF TULSA, OKLAHOMA, ASSIGNOR TO BRADEN STEEL & WINCH COMPANY, OF TULSA, OKLAHOMA.

DERRICK REINFORCEMENT.

Application filed January 13, 1928. Serial No. 246,525.

My invention consists in new and useful improvements in clamping means for securing a releg or reenforcing leg to the common leg of a derrick, skeleton tower or the like 5 employed in connection with oil wells, and has for its object to provide an arrangement of the above character particularly adapted for use with I-beams or channel irons when employed as relegs.

10 Another object of my invention is to provide a structure which may be easily assembled and dismantled, and one which will securely hold the several parts of the derrick reinforcement in position.

15 A still further object and advantage of my construction resides in the fact that bolts, screws and rivets are unnecessary in its application to the derrick, thus affording a simple reenforcing structure of the maximum 20 salvage value.

With the above and other objects in view which will appear as the description proceeds, my invention consists in the novel features herein set forth, illustrated in the accompanying drawing, and more particularly 25 pointed out in the appended claims.

Referring to the drawing, in which numerals of like character designate similar parts throughout the several views,

30 Fig. 1 is a perspective view in side elevation, partly broken away, showing a section of a derrick leg with my improved reenforcing means, and clamping device applied thereto.

35 Fig. 2 is a cross section taken on line 2—2 of Fig. 1.

Fig. 3 is a cross section taken on line 3—3 of Fig. 1, and

Fig. 4 is a view somewhat similar to Fig. 40 1, but from a different angle, showing the reenforcing and clamping members in place.

In the drawings, 1 represents a common leg 45 of the derrick consisting of the usual angle iron supported on a suitable base 2, said leg being provided at the central portion of the angle on its outer face, at predetermined points throughout its length, with bent bars 3 secured thereto by welding or other suitable means. 4 designates the usual outer 50 clamping plate or corner plate which is V-shaped, and fits tightly against the outer face of the leg 1, being provided with a plurality of key slots 5, for gripping the ends of brace rods when the derrick is assembled.

6 and 7 represent upper and lower sections 55 of the releg or supporting leg, which, as shown in the drawing, consist of I-beams mounted adjacent the center of the outer face of each common leg of the derrick. The abutting vertical ends of each of the I-beams 60 6 and 7 are provided with vertically extending slots 8, adapted to engage the bent bar arrangement 3 on the common leg 1, when said I-beams are in position, as clearly shown in Figs. 1 and 4 of the drawing. Toward the 65 upper end of each section of the I-beam reinforcement, and centrally of the web thereof, I provide an aperture 9, as shown on the lower section 7 in Fig. 1.

10 represents a hook bar or clamping bar, 70 substantially V-shaped and provided at each end with an inwardly bent hook member 11, adapted to engage the vertical edges of the common leg 1 of the derrick. The central portion of the clamp bar 10 is bent to form a 75 looped ear 12, adapted to register with and extend through the aperture 9 in the web of the I-beam, as shown in Figs. 1 and 2, and receives a standard wedge pin 13, to secure the I-beams in place. This clamp bar 10 is 80 preferably composed of substantially resilient metal, whereby one of said hook members 11 may be hooked over one of the vertical edges of the common leg 1, and by striking a light blow on the side of the ear 12, the opposite hook member 11 will snap around the other side of the common leg of the derrick and securely grip the same. The clamp bar may be easily removed by prying off with any 85 pointed instrument. 90

It will be noted that when the several parts are assembled, the toes and web of the I-beam relegs come into bearing on the corner plate 4 at approximately the same time, the toes striking slightly in advance of the web. The 95 wedge pin 13 has a tendency to line the I-beams up squarely behind the angle leg 1 of the derrick, and when said pin is driven tight, the web of the I-beams will come into bearing on the corner plate 4, and prevent the pressure of said wedge springing the I-beams 100 out of shape.

It will also be noted that the toes of the I-beams will hold the clamp bar 10 in position, so that the hooks 11 will come into position 105 around the common leg 1, when the wedge is driven tight.

The bent bar 3, besides serving as means for

holding the I-beam sections in line, may be used as a means for locking the wedge pin 13 in place when the structure is assembled.

From the foregoing, it is believed that my invention may be clearly understood by those skilled in the art without further description, it being borne in mind that numerous changes may be made in the details of construction without departing from the spirit of the invention as set forth in the following claims.

What I claim and desire to secure by Letters Patent is:

1. In a derrick, the combination of angle iron leg members suitably joined in a derrick structure, secondary leg members consisting of lengths of I-beams having slotted extremities, bent bars secured to and projecting from said angle iron leg members, adjacent the abutting extremities of said I-beams, said slots in the latter being adapted to engage said bent bars, whereby said I-beams are secured together in continuous string arrangement for reenforcing said primary leg members during heavy duty, and means removably securing said secondary members to said angle iron members.

2. A clamping bar for securing a releg to the angle iron main leg of a derrick, comprising a strip of resilient metal bent substantially V-shaped and terminating in an inwardly bent hook at each end, the central portion of

said strip forming a looped ear, the arms of said V being parallel to and lying against the adjacent surfaces of the angle iron leg, said hooks being adapted to engage the vertical edges of the main leg, said looped ear passing through an aperture in said releg, and a wedge pin for engaging said ear and securing said parts together.

3. In a derrick, the combination of angle iron leg members suitably joined in a derrick structure, secondary leg members consisting of lengths of I-beams secured together in continuous string arrangement, for reenforcing said angle legs, clamping bars for securing said I-beams to said angle legs, each comprising a strip of resilient metal bent substantially V-shaped and terminating in an inwardly bent hook at each end, the central portion of said strip forming a looped ear, the arms of said V being parallel to and lying against the adjacent surfaces of said angle legs, said hooks being adapted to engage the vertical edges of the angle legs, said looped ear passing through an aperture in the web of said I-beam, and a wedge pin for engaging said ear, and securing the parts together with the inner vertical edges of said I-beams engaging the outer surfaces of the arms of said V-shaped strip.

In testimony whereof I affix my signature.

ARTHUR L. DAY.
